FREDERIC BILLON, OF SOLOTHURN, SWITZERLAND, ASSIGNOR TO THE FIRM
SCINTILLA, OF SOLOTHURN, SWITZERLAND.

ELECTRIC STARTER FOR INTERNAL-COMBUSTION ENGINES.

1,416,326.

Specification of Letters Patent. Patented May 16, 1922.

Application filed January 18, 1922. Serial No. 530,156.

To all whom it may concern:

Be it known that I, FREDERIC BILLON, a citizen of the Swiss Republic, residing at No. 532 St. Niklausstrasse, Solothurn, Switzerland, have made certain new and useful Improvements in Electric Starters for Internal-Combustion Engines, of which the following is a specification.

10 Electro-motive starting apparatus for internal combustion engines have already been proposed wherein an intermediate wheel capable of being rocked between the pinion and the toothed wheel is moved along by an electro-magnetically actuated clutch member. After the engagement has been effected the intermediate wheel disengages itself again automatically and immediately it has come into mesh with the above mentioned two toothed wheels. For throwing 20 the starting motor into and out of gear an electro-magnetically actuated switch is employed which automatically cuts out the starting motor when the internal combustion engine is running.

25 According to the present invention the two electro-magnetically actuated devices, namely, the clutch member and the automatic main switch are combined together.

One embodiment of this invention is illustrated in the accompanying drawings in which:—

Figure 1 is a diagram of the electrical connections of the starting motor, and

Figures 2 and 3 illustrate constructional details of the improved starting apparatus in cross-section and longitudinal section respectively, Figure 2 being a section on the line A—B of Figure 3.

In the illustrated embodiment the motor 40 may be switched-in through a resistance-step.

45 In these drawings:—*a* is the starting electric motor which drives the internal combustion engine through the gears *b*, *d*, *d'* and *c*. The swinging intermediate gears *d* and *d'* are rotatably mounted in and oscillatable with a rocking sleeve *e*. The gear *c* is attached to the engine shaft (not shown) and the gear *d'* is brought into engagement therewith by the excitation of the electro-magnetic clutch *f*, to the movable armature *g* of which the switch member *i* of the main motor controlling switch is fixed in an insulated manner.

50 The relatively small gear wheel or pinion *b* is attached directly to the terminal of the

motor shaft *a'* and is in permanent mesh with the gear *d* rotatably mounted in the sleeve *e* and preferably formed as a unit with the gear *d'*. The sleeve *e* is suitably mounted for swinging movement in the frame structure *a²* of the starting motor *a* and the axis of its swinging movement is coincident with the axis of the motor shaft *a'*. A flanged brake disk *v* is non-rotatively secured upon the polygonal extremity of the motor shaft *a'* outwardly of the pinion *b* and a suitable type of thrust bearing *v'* is arranged between the end of the motor frame *a²* and the brake disk *v* to limit the outward movement of the latter longitudinally of the shaft *a'*.

The sleeve *e* is so mounted as to have a limited movement longitudinally with respect to the axis of the shaft *a'* and when moved in one direction its internal flange *e²* is brought into frictional engagement with the brake disk, and said sleeve accordingly rotates with the shaft *a'* and the brake disk.

The electro-magnetic clutch consists of a coil, which is suitably housed in the frame structure *a²*, and the armature *g* which latter is of ring-like form and is mounted for movement longitudinally with respect to the shaft *a'*. An expansion coil spring *z* is so arranged with respect to the movable armature *g* as to normally move the latter away from the magnet coil.

The armature *g* is provided at opposed points with laterally projecting pins *t* which project through guide apertures *t'* in the frame structure *a²* and are engageable with a pressure plate *u* which latter is interposed between the oscillatable sleeve *e* and the magnet coil *f* whereby upon energization of the latter, the armature *g* is attracted and the pins *t* move therewith engaging the plate *u* and move the latter, together with the sleeve *e*, thereby causing the internal flange *e²* of the latter to engage 100 the brake drum *v*.

The plate *u* is normally held against rotation and maintained in a predetermined position with respect to the motor frame structure *a²* by the tension of a pair of opposed springs *y* and thus during the initial turning movement of the sleeve *e* with the shaft *a'*, the plate *u* is held stationary, however, as the swinging movement of the sleeve *e* is completed and the gear *d'*, is brought into mesh with the engine gear wheel *c* the shoulders *e'* in the sleeve *e* en-

gage the laterally projecting pins u' and the latter is turned with the sleeve against the tension of one of the springs y . The plate u is provided with transverse openings s which are so disposed with respect to the armature g that, when the intermediate gear d' is in proper mesh with the gear wheel c , the pins t register with the openings s and permit further movement of the armature g under the influence of the magnetic attraction of the coil f . The sleeve e is yieldably retained in its operative and inoperative positions by means of a spring actuated member e^3 engageable in notches e^4 formed in the sleeve.

The movable switch member i is carried by and movable with the armature g and during the initial movement of the armature the switch member i engages the relatively stationary contact member 1 and closes a circuit to the starting motor a in which is interposed a resistance unit w and a source of electro-motive force m . During the subsequent movement of the armature g incident to the entry of the pins into the opening s of the plate u the movable contact member i engages the contact 2 and cuts out the resistance unit w thereby causing the starting motor a to develop its full power.

The operation is as follows:—

By closing the key k the coil f is energized from the battery m and it attracts and moves the armature disc g until the guide pins t press against and shift the locking plate u , together with the rocking sleeve e , the latter being pressed against the brake disc v . Incident to the movement of the armature plate g , the main switch i closes the contact 1 whereby the motor a is switched-in through the resistance w and begins to revolve. The disc v which rotates with the motor shaft carries along with it by friction the rocking sleeve e , said sleeve moving through the angle α Fig. 2, and throws the intermediate gear d' into mesh with the ring of teeth c of the internal combustion engine.

When, during this meshing movement the rocking sleeve is rotated through the angle β , the pins u' are engaged by the shoulders e' and hence the locking plate u turns with the sleeve until the guide pins t coincide with the holes s in the plate u , so that the armature disc g can now be further attracted without hindrance. The main switch i advances at the same time on to the contact 2 so that the resistance w is cut out from the circuit or short-circuited, and the starting motor a is caused to develop its full torque. When the guide pins t have been pushed completely home, the pressure upon the locking sleeve e and the brake disk v is released. At the moment when the pressure on the sleeve e is released by the

entry of the pins into the holes s , the torque of the motor, which latter is developing its maximum power, maintains the gear d' in mesh with the engine gear e , but when the explosive engine has started, the gear e kicks the gear d' out of mesh, thereby disconnecting the starter from the engine.

Immediately the engine is started, the key k is released and the circuit of the magnet coil f being thus opened, the armature g is detached from the magnet f by the action of the spring z ; the switch i opens the motor circuit; the starting motor a stops; and the locking plate u is returned into its initial position by the action of the spring y .

What I claim is:—

1. In an electric starter for internal combustion engines, the combination with an electric starting motor, a pinion connected with said motor, a toothed wheel adapted for connection with the internal combustion engine, an intermediate toothed gear actuated by said pinion, an oscillatable support for said intermediate gear, of an electro-magnetically actuated clutch device operable to clutch the oscillatable support with the starting motor whereby the first mentioned toothed gear is brought into mesh with the engine wheel, a motor circuit, and a main switch interposed in the motor circuit, controlling said electric motor and actuated by said clutch device.

2. In an electric starter in the combination claimed in claim 1, the feature that the movable contact of the electro-magnetically actuated main switch is located on the armature of the electro-magnetic clutch.

3. In an electric starter comprising the combination claimed in claim 1, the further combination therewith of a resistance-step interposed in the motor circuit and arranged in the operative path of the movable contact of the main switch, a movable locking plate having a plurality of apertures therein and actuated by the oscillatable support, a corresponding plurality of projections on the armature of the electro-magnetic clutch device adapted to enter said apertures as the intermediate gear meshes with the engine gear and permit further movement of the clutch device independently of the oscillatable support whereby the resistance step is cut out.

4. In an electric starter comprising the combination claimed in claim 1, the feature that the oscillatable support is mounted for movement axially of the starting motor shaft under the influence of the magnetically actuated clutch device and is engageable with a brake member actuated by said motor shaft.

In testimony whereof I have signed my name to this specification.

FREDERIC BILLON.
